UNITED STATES PATENT OFFICE.

PAUL B. PARKS, OF OAK PARK, AND DONALD W. MILLER, OF ELMHURST, ILLINOIS,
ASSIGNORS TO VAPOR CAR HEATING COMPANY, INC., OF CHICAGO, ILLINOIS, A
CORPORATION OF NEW YORK.

AUTOMATIC SWITCH.

Original application filed February 2, 1927, Serial No. 165,392, and in Sweden August 14, 1925. Divided
and this application filed October 5, 1927. Serial No. 224,184.

This invention relates to a new and improved automatic selector switch, which is of general application but is particularly adapted for use in connection with a car heating system such as is disclosed in our copending application, Serial No. 165,392, filed February 2, 1927, in which this selector switch was first disclosed, and of which parent application this present application 10 is a division.

This improved switch comprises a Bourdon tube which is closed at one end and is in open communication at the other end with a pipe line on the car which contains air or other fluid under pressure when the car is connected in service in a train. The free closed end of the Bourdon tube is connected through quick-motion mechanism with a movable switch-plate or bridge-plate adapted to be moved into or out of engagement with a plurality of fixed spring contacts so as to form an electrical connection between these several contacts. Mechanism is also provided for manually moving one of the 15 spring contacts out of engagement with the bridge-plate, even though these contacts have been brought into engagement automatically by the withdrawal of fluid pressure from the Bourdon tube. Automatic means is provided 20 whereby this manually operated mechanism will be automatically moved back to disengaged position when fluid pressure is returned to the tube.

The principal object of this invention is 25 to provide an automatic selector switch constructed and functioning in the manner briefly indicated hereinabove, and as described more in detail hereinafter.

Another object is to provide means in connection with said selector switch whereby a portion of the circuits automatically closed by this switch may be broken manually in emergency conditions, this emergency mechanism being automatically thrown out of 40 operation so that the parts will be returned to their normal positions.

Other objects and advantages of this invention will be apparent from the following detailed description of one approved form 45 of the mechanism.

In the accompanying drawings:

Fig. 1 is an elevation of the automatic se-

lector switch, with the cover plate of the enclosing casing removed.

Fig. 2 is a vertical section, taken substantially on the line 2—2 of Fig. 1.

Fig. 3 is an elevation of a portion of the switch operating mechanism, the manually operable releasing mechanism being removed to disclose the parts located thereinunder, and other parts being broken away to facilitate the disclosure.

In our parent application, Serial No. 165,392, hereinabove referred to, we have disclosed an electrical control system for regulating the temperatures in a plurality of separate compartments of a railway car. This regulating system comprises a number of control circuits, two of which are automatically opened or closed by the automatic selector switch hereinafter described.

The automatic selector switch K, with which the subject-matter of the present application is particularly concerned, comprises a casing 67 in which is mounted a Bourdon tube 68, preferably of the shape and cross section indicated in Figs. 1 and 2. The free end 69 of this tube is closed, and the other end is mounted on and is in open communication with the pipe 70 leading to the main air line on the car. Three similar spring contacts 71, 72 and 73 are mounted in parallel relation on an insulating block 74 within casing 67. The contacts 71 and 72 are in one of the control circuits of the heating system, and contacts 72 and 73 are in a second circuit, all as disclosed in detail in said parent application. A swinging contact plate 75 mounted on insulating block 76 is adapted to bridge these three contacts 71, 72 and 73 when in the position shown in Figs. 1 and 2. When swung up to the position indicated in dotted lines in Fig. 3, the plate 75 will be out of contact with the several spring contacts 71, 72 and 73 so that there will be no electrical connection between any two of these contacts. The insulating block 76 which carries movable contact 75 is mounted on a plate 77 which is pivoted on the fixed post 78. Plate 77 has at one side a triangular projection 79 adapted to be engaged by a roller 80 mounted in the free end of a link 81, pivoted at 82 on a bellcrank 83, which is mounted on a fixed pivot 84. Link 81 is con-

stantly urged toward the right in Figs. 1 and 3 by means of the contraction spring 85, one end of which is secured to the link 81 and the other to a fixed portion of the supporting framework at 85'. A composite link 86, which link is adjustable at 87, is connected at one end 88 to the free end 69 of the Bourdon tube 68, and is adjustably connected at its other end 89 within a slot 90 in one arm 10 of bellcrank 83. When the car is out of service and the air pressure in pipe 70 and Bourdon tube 68 is dissipated, this tube will contract so that the free end 69 will move inwardly and downwardly and the parts of the 15 switch mechanism will assume the positions shown in Figs. 1 and 3. The roller 80 will be in engagement with the upper inclined surface of projection 79 and will hold the bridge plate 75 in engagement with the spring 20 contacts 71, 72 and 73. When super-atmospheric air pressure is returned to the pipe 70, the tube 68 will tend to straighten and will pull up on the link 86, swinging bellcrank 83 in a counter clockwise direction and 25 drawing down the link 81, the roller 80 moving downwardly and to the left along the inclined surface of projection 79 until it passes the pointed end of this projection. The spring 85 will then draw the roller to the 30 right along the downwardly inclined surface of projection 79, thus quickly rotating the plate 77 in a clockwise direction and quickly swinging the bridge plate 75 out of contact with the spring contacts 71, 72 and 73. When 35 the air pressure is released from pipe 70 and Bourdon tube 68, a reversal of these movements will take place and the contact plate 75 will be quickly snapped back into the position shown in Figs. 1 and 2 so that the contacts 71, 72 and 73 are again placed in electrical connection with one another by means 40 of bridge plate 75. A projecting finger 150 on the left-hand arm of bellcrank 83 is adapted to engage the fixed pin 151 to limit movement of the parts to the switch-closing position shown in Figs. 1 and 3. The lower fixed plate 152 and upper fixed plate 153 serve as anchoring means for the several pivot pins and abutment pins.

50 Under certain conditions it is desirable to break the electrical connection between spring contact 73 and bridge plate 75 without disturbing the connection between contacts 71 and 72 and the plate 75. Accordingly, means are provided for independently pushing back the spring contact 73 out of contact with plate 75 when the parts are in the positions shown in Figs. 1 and 3. A plate 55 91 pivoted on the central post 154 carries a block of insulating material 92, which, when the plate is swung in a clockwise direction from the position shown in Fig. 1, engages the spring contact 73 and pushes it back to the position shown in dotted lines in Fig. 2 60 and out of contact with the bridge plate 75.

An oppositely extending arm 93 of plate 91 has a slotted portion 94 into which extends a fixed pin or post 95 for limiting the arcuate swinging movement of the plate. A second spring arm 96, extending from arm 93, has a curved or humped portion 97 adapted to snap over the top of a pin 98 which is fixed on the pivoted bellcrank 83. A coil spring 99, having one end fixed and the other end engaging the arm 93, tends to swing the plate 91 into the inoperative position shown in full lines in Fig. 1. However, when the spring clamp 97 is in engagement with the end of post 98, the insulating block 92 will be held in its operative engagement so as to push back the spring contact 73, the coil spring 99 being at such time under tension. When the bellcrank 83 is swung down by the expansion of the Bourdon tube 68 so as to swing up the contact plate 75 to its circuit-breaking position, as shown in dotted lines in Fig. 3, the post 98 will be moved down out of engagement with the spring clamp 97 thus leaving the spring 99 free to swing the plate 91 back to its inoperative position as indicated in Fig. 1. An operating knob or handle 200 is secured centrally to the plate 91 and extends out through the cover plate 156 of casing 67 so that it may be manually grasped to swing the releasing plate 91 to either of its two 65 positions. The mechanism just described constitutes an emergency switch which is operated when the car is out of service, if it is desired to heat the car to one of the higher 70 temperatures. It will be apparent that even though this emergency switch has been operated, it will be automatically returned to its inoperative position by the spring 99 when the car is again put in service and fluid pressure is returned to the Bourdon tube 68. 75

We claim:

1. A pressure-operated selector switch comprising a plurality of spring contacts, a movable switch-plate, fluid-pressure operated means for moving the switch-plate into or out of engagement with the spring contacts, and means for independently moving one of the spring-contacts out of engagement with the switch-plate. 100

2. A pressure-operated selector switch comprising a plurality of spring contacts, a movable switch-plate, fluid-pressure operated means for moving the switch plate into or out of engagement with the spring contacts, releasing means movable into engagement with one of the spring contacts to hold it out of engagement with the switch-plate, a spring for automatically returning the releasing means to its inoperative position, and a latch for holding the releasing means in engagement with the spring contact, the latch being released when the fluid-pressure operated means moves the switch-plate out of engagement with the spring contacts. 105

3. A pressure-operated-selector-switch-com- 110

prising a plurality of spring contacts, a movable switch-plate, fluid-pressure operated means for moving the switch plate into or out of engagement with the spring contacts, releasing means movable into engagement with one of the spring contacts to hold it out of engagement with the switch-plate, a spring for automatically returning the releasing means to its inoperative position, a latch on the releasing means, and an abutment on a portion of the fluid-pressure operated means engaged by the latch to hold the releasing means in operative position only while the switch-plate is in engagement with the spring-contacts.

4. A pressure-operated selector switch comprising a Bourdon tube, a plurality of spring contacts, a movable switch plate adapted in one position to engage and electrically connect the spring contacts, connections between the free end of the tube and the movable switch plate adapted to move the plate into or out of contact making position, and means for moving one of the spring contacts out of engagement with the switch plate.

5. A pressure-operated selector switch comprising a Bourdon tube, a plurality of spring contacts, a movable switch plate adapted in one position to engage and electrically connect the spring contacts, connections between the free end of the tube and the movable switch plate adapted to move the plate into or out of contact making position, means movable into engagement with one of the spring contacts for springing it back out of engagement with the switch plate, and means for automatically returning the last named means to inoperative position.

6. A pressure-operated selector switch comprising a Bourdon tube, a plurality of spring contacts, a movable switch plate adapted in one position to engage and electrically connect the spring contacts, connections between the free end of the tube and the movable switch plate adapted to move the plate into or out of contact making position, a block movable into engagement with one of the spring contacts for moving it back out of engagement with the switch plate, a spring for returning the block to inoperative position, and a latch for holding the block in operative position against the action of the spring, the latch being released by the movement of the switch plate to contact-breaking position.

7. A pressure operated selector switch comprising a Bourdon tube, a plurality of spring contacts, a movable switch plate adapted in one position to engage and electrically connect the spring contacts, quick-motion connections between the free end of the tube and the switch-plate adapted to move the plate into or out of contact-making position, said connections comprising a pivoted plate, a block movable into engagement with one of the spring contacts for moving it back out of engagement with the switch plate, a spring for returning the block to inoperative position, a spring-latch connected with the block, and an abutment on the pivoted plate engaged by the latch to hold the block against the action of the spring, the abutment being moved out of engagement with the latch when the switch-plate is moved to contact-breaking position.

8. A pressure-operated selector switch comprising a Bourdon tube, a plurality of spring contacts, a pivoted switch-plate adapted to be swung into or out of engagement with the spring contacts, there being a cam projection on the switch-plate, a bell-crank lever, a link connecting one arm of the bellcrank with the free end of the Bourdon tube, a link pivoted at one end to the other arm of the bellcrank, a roller pivoted in the free end of the link and engaging the cam, and a spring mounted to urge the roller toward the cam.

9. A pressure operated selector switch comprising a Bourdon tube, a plurality of spring contacts, a pivoted switch-plate adapted to be swung into or out of engagement with the spring contacts, there being a cam projection on the switch-plate, a bellcrank lever, a link connecting one arm of the bellcrank with the free end of the Bourdon tube, a link pivoted at one end to the other arm of the bellcrank, a roller pivoted in the free end of the link and engaging the cam, a spring mounted to urge the roller toward the cam, a pivoted member movable into engagement with one of the spring contacts to move it out of engagement with the switch-plate, a spring tending to return the pivoted member to inoperative position, a spring-latch on the pivoted member, and an abutment on the bellcrank engaged by the latch to hold the member in operative position.
